UNDERGARMENT

Lorenzo Curcio, Philadelphia, Pa.

Application August 8, 1936, Serial No. 94,970

2 Claims. (Cl. 2-224)

My invention relates to a new and useful undergarment and it relates more particularly to men's shorts or trunks used as a nethergarment, as well as long-leg undergarment.

5 The object of my invention is to provide a nethergarment of this character which will be more comfortable, which will prevent chafing and which will be self-supporting and which will possess certain other desirable characteristics 10 not heretofore embodied in nethergarments. This application is a substitute for my previous application, Serial No. 719,062 filed April 5, 1934.

For the purpose of illustrating my invention, I have shown in the accompanying drawings, 15 one form thereof which is at present preferred by me, since the same has been found in practice to give satisfactory and reliable results, although it is to be understood that the various instrumentalities of which my invention consists 20 can be variously arranged and organized and that my invention is not limited to the precise arrangement and organization of the instrumentalities as herein shown and described.

Referring to the drawings in which like reference characters indicate like parts:

Figure 1 represents a perspective view of the nethergarment embodying my invention.

Figure 2 is a section generally on line 2-2 of Figure 1.

30 Figure 3 is a section generally on line 3-3 of Figure 2.

Figure 4 is an enlarged fragmentary sectional view taken generally on line 4-4 of Figure 3.

Figure 5 represents a plan view of one of the 35 two half body sections of the garment laid out flat.

Figure 6 represents a similar plan view of the partition panel.

Figure 7 represents a similar plan view of one 40 of the two waist sections.

Figure 8 represents a similar plan view of one of the two diagonal reinforcing strips.

The nethergarment of my present invention is generally of the bifurcated type, and is formed 45 of two more or less similar halves designated generally by A and B, which are composed of two more or less similar body sections 10 illustrated particularly in Figure 5. The edge 11 and the edge portion 12 of each body section 10 is seamed 50 together to form the leg portions, by means of the similar seams 13-A and 13-B, while the edge 14 of the two similar body sections 10 is seamed together to form the rear seam 15. The similar curved edges 16 on the two body sections 55 10 are united to form the crotch seam 17 in

direct continuation of the rear seam 15. The portions 18 serve to form the two overlapping front fly portions 19 and 20 respectively. It will be seen that by this novel construction, the leg seams 13-A and 13-B are somewhat to the rear of the center of the crotch, and but a single seam is provided in each leg. The lower edge 21 is folded in and hemmed as at 22 to provide suitable edging. A partition panel 23 is mounted in one side of the garment, as indicated particularly 10 in Figures 1, 2 and 3 with the edge 24 thereof seamed into the leg seam 13-B so that lower edge 25 (which is suitably hemmed) is disposed slightly above the lower edge of the corresponding leg B as indicated particularly in Figures 1 15 and 3, and so that the upper edge 26 (also suitably hemmed) is approximately at the crotch line. The upright edge 27 on the other hand, is then sewn to the side of the leg along the seam 28, terminating in the waist zone as at 29. The proportions are so arranged that the transverse 20 span of the member 23 is slightly less than the corresponding spanned portion of the leg of the garment, so that the panel 23 will normally tend 25 to stand away from the side of the leg B.

The upper edge 30 of each of the body sections 10 is suitably Shirred or gathered more or less at the points 31 so as to give fullness in the garment, and to the thus shirred or gathered edges, the waist band sections 32 and re-inforcing sections 33 are sewn. The re-inforcing section 33 is so cut that the warp indicated by the shade lines, runs parallel to the inclined edge 34 thereof, while the waist band section 32 is so cut that the warp thereof runs parallel to the horizontal edge 35 thereof. It is to be understood that these two pieces could also be cut so that the weft would run in these mentioned directions;—the requirement being merely that in the waist band section 32, there shall be threads (either warp or weft) running parallel to the edge 35, while in the reinforcing sections, a set of threads (either warp or weft) should run generally parallel to the edge 34. The edge 35 and the edge 36 are then united by a line of sewn 40 stitches (invisible in the finished garment), indicated at 37 in Figure 4, and the inclined edge 34 (suitably turned in) of the re-inforcing sections 33, together with the rear portion of the edges 35, is then sewn to the upper edges 30 of the respective body section 10 by a line of sewn 45 stitches indicated at 39 in Figure 4, also invisible in the finished garment. Then, the members 32 and 33 are folded over along the edge 40, and the edge 38 of the waist section (also suitably 50 55

folded in) is then sewn to the body sections 10 of the garment along the line of sewn stitches 41. The front fly of the garment is then suitably finished as indicated in Figures 1 and 3 of the drawings. A series of button-holes 42 may be provided in the waist band section 43 of the garment, on either side, and an adjustment strap (of fabric or the like), sewed to the waist band at 44 and provided with a series of buttons 45, 10 may be provided for effecting adjustment in the effective circumferential dimension of the waist band. The waist band is then fastened in the front by suitable fastening means as buttons and button-holes 46 and 47.

15 By reason of the diagonal disposition of the threads in the re-inforcing sections 33, the natural "give" in the fabric of the garment is counteracted on the bias, so that the front of the garment will give better support to the abdominal 20 regions bounded thereby, and the tendency to distort the garment is thus also prevented.

Having thus described my invention, what I hereby claim as new and desire to secure by Letters Patent, is:

25 1. A men's bifurcated nethergarment comprising two leg sections united to each other along a rear seam and crotch seam, and a generally upright partition section in one of the two leg sections having a short rear edge thereof secured to the inner side of the leg somewhat behind the center of the crotch said rear partition

edge being separate and distinct from the rear seam and spaced somewhat ahead of said rear seam, and having the front thereof secured to the inner side of the leg somewhat in advance of the center of the crotch the partition section being otherwise unsecured to the nethergarment; the partition wall being spaced substantially to one side of the vertical median plane of the garment, and said partition section being contained wholly within said leg section. 10

2. A men's bifurcated nethergarment comprising two leg sections united to each other along a rear seam and crotch seam, and a generally upright partition section in one of the two leg sections having a short rear edge thereof secured to the inner side of the leg somewhat behind the center of the crotch, said rear partition edge being separate and distinct from the rear seam and spaced somewhat ahead of said rear seam, and having the front thereof secured to the inner side of the leg somewhat in advance of the center of the crotch the partition section being otherwise unsecured to the nethergarment; the partition wall being spaced substantially to one side of the vertical median plane of the garment, and said partition section being contained wholly within said leg section, and having an upper seamed edge extending upwardly from a point ahead of the rear towards the front of the garment. 15 20 25 30

LORENZO CURCIO.
